UNITED STATES PATENT OFFICE.

ROLLAND T. CASE, OF LA CROSSE, WISCONSIN.

APPARATUS FOR FORMING DENTAL INLAY CASTINGS.

Application filed December 29, 1920. Serial No. 433,904.

To all whom it may concern:

Be it known that I, ROLLAND T. CASE, a citizen of the United States, and resident of La Crosse, in the county of La Crosse and State of Wisconsin, have invented new and useful Improvements in Apparatus for Forming Dental Inlay Castings, of which the following is a description, reference being had to the accompanying drawings, which are a part of this specification.

This invention relates to improvements in apparatus for forming dental inlay castings.

In inlay casting precious or other metals, a mold is formed around a wax pattern and when completed the wax is melted and discharged from the mold. The mold is formed with a tapered mouth leading to the recess in which the casting is made. In ordinary practice, the mold is mounted on a revolute member and a crucible containing the molten metal is also placed on the revolute member adjacent the mouth of the mold and upon rapidly revolving the member horizontally the molten metal is discharged by centrifugal force from the crucible into the mouth of the mold and then into the recess of the mold where it quickly cools and becomes hard. When hard the mold is broken to remove the casting.

As there is a perceptible space between the crucible and the mouth of the mold and from the outer portion of the mouth to the mold recess, the molten metal in passing from the crucible passes through the space and drops on the

inclined portion of the mouth of the mold and climbs up said inclined portion and into the mold recess, and is more or less chilled before it reaches said mold recess with the result that the metal does not completely fill

all of the minute crevices of the mold recess and the casting is not as perfect as could be desired. Furthermore, the molten mass of metal in passing from the crucible to the mouth portion of the mold and divide into small particles, and these small particles will become chilled and partly hard before they enter the mold and form an imperfect casting.

The crucibles used in dental inlay casting are comparatively expensive and very often crack or break when used but a few times.

It is one of the objects of the present invention to overcome the before mentioned objectionable features and provide an apparatus for forming dental inlay castings in

which the molten metal is guided and driven into the mold recess in the most direct and efficient manner without permitting the molten metal to splash or to become chilled before it enters the mold recess.

A further object of the invention is to provide an apparatus for forming dental inlay castings in which the crucible and the mold are integral and are newly constructed for each inlay casting made and are destroyed to remove the casting.

A further object of the invention is to provide an apparatus for forming dental inlay castings in which the wax pattern may be so positioned on the sprue pin as to form a mold with the casting recess located so that in supplying molten metal to the recess, gravity as well as centrifugal force will assist in filling the recess.

A further object of the invention is to provide a method of and apparatus for forming dental inlay castings in which the operator may easily change the form of the crucible portion of the apparatus which holds the molten metal to suit any condition which might arise in casting unusual shapes or rotating the mold in any direction.

A further object of the invention is to provide an apparatus for casting dental inlays which is of simple construction, is efficient in operation and is well adapted for the purpose described.

With the above and other objects in view, the invention consists of the improved apparatus for forming dental inlay castings and its parts and combinations as set forth in the claims, and all equivalents thereof.

In the accompanying drawings, in which the same reference characters indicate the same parts in all of the views:

Fig. 1 is a perspective view of a portion of the apparatus used in forming the combined crucible and casting mold;

Fig. 2 is a perspective view of another portion of the apparatus used in forming the combined crucible and mold;

Fig. 3 is a side view, parts being shown in section, of the apparatus illustrating one of the steps in using the improved apparatus; and

Fig. 4 is a perspective view of the combined crucible and mold illustrating another step in the use of the apparatus.

Referring to the drawings, the apparatus used in carrying on the steps of the im-

proved molding process consists of a tubular flask 16, a main body member and sprue pin holder 17, a crucible bowl former 18 and a sprue pin 19.

5 The flask 16 is preferably of cylindrical form with its lower half section cut away as indicated by the numeral 16' to receive the inner flat face portion 17' of the main body member 17 as shown in Fig. 3. Said main 10 body member 17 is formed with vertically extending dovetail grooveways 20 for slidably receiving the vertically extending dovetail guides 21 on the inner flat face 18' of the the bowl former 18 and for holding the body 15 member and bowl former firmly in assembled position, as also shown in Fig. 3. The bowl former is provided with a medial outwardly projecting rounded bowl former portion 22 which merges upwardly into a half conical portion 23 which with a half conical portion 24 extending upwardly from the body portion 17 forms a conical upper portion. The apex of the body conical portion is formed with a vertical opening 25, for receiving the 20 sprue pin 19, which supports the pattern 26 preferably formed of wax.

The inner face of the body member 17 is also provided with guide grooves 27 into which slidably extend the edge portions 28 30 of the flask 16. Several sets of these guide grooves are provided to accommodate flasks of different sizes.

The upper face of the body member is formed with half circular shoulders 29 in 35 stepped formation to fit different sizes of flasks and over one of which shoulders the half circular edge portion 30 of the flask extends and holds the parts together. In carrying out the steps of the method, the wax 40 pattern is made of the tooth cavity or other part and is mounted on the upper end portion of the sprue pin 19 and said pin is inserted in the pin hole 25 of the body member and the bowl former member 18 which 45 have been assembled. The flask tube 16 is now placed over the bowl former member and the half circular portion of the body portion member and an investment compound or other molding material 31, while in 50 a plastic condition, is poured into the upper open end of the flask tube while the lower end of the tube is closed by the surface it is resting upon. As soon as the investment compound has set or become hard, the body 55 is slid downwardly in a line parallel to the flask to disengage the bowl former member and the mouth forming sprue pin, or the sprue pin may also move downwardly with the body member, or removed as desired.

60 When these two parts are removed, the bowl former member may be easily removed laterally, and upon the application of heat to the pattern 26, it will melt and flow out of the molded recess 31. The resultant mold 65 comprises the mold recess 31, before men-

tioned, the integral crucible bowl portion 32 and the tapered mouth 33 leading directly into the mold recess 31. The combined mold and crucible is now placed in the centrifugal casting machine of ordinary construction, 70 and the metal to be fused is placed in the crucible and melted by a flame and blow pipe. When the metal is at the proper temperature, the casting machine is rotated to cause the molten metal to travel upwardly directly into the mouth of the mold and into the mold recess by centrifugal force in a most direct path without loss of metal or heat, and the metal will completely fill the mold recess while in a fused state and as 75 cooled by further rotation of the mold a perfect casting will be made. When the casting operation is completed, the investment material is broken and removed from the tubular flask to remove the casting. In making special castings the crucible bowl may be easily scraped to any desired shape to direct the molten metal into the mold, and the pattern may be mounted upon the sprue pin to position the casting recess at any 80 location with respect to the mouth of the recess to aid the flow of the metal there-through. By positioning the major portion of the pattern on the side of the sprue pin nearest to what will be the bottom of the mold, the course of the molten metal will be mostly downwardly after it passes through the mouth of the mold, with the result that 85 gravity will materially aid in filling the mold.

From the foregoing description, it will be seen that the improved apparatus provides a new crucible and mold for each casting and that the integral construction eliminates many undesirable features adherent to methods and apparatus now in general use.

What I claim as my invention is:

1. Means for forming a mold, comprising a body member, a sprue pin removably connected thereto for supporting a pattern, a crucible bowl forming member to permit the removal of the mold removably connected to the body member, and a tubular flask member inclosing the sprue pin and the bowl forming member for receiving an investment compound while in a fluid state to form when hard a mold having an integral crucible portion.

2. Means for forming a mold, comprising a body member, a sprue pin removably connected thereto for supporting a disappearing pattern, a crucible bowl forming member slidably removably connected to the body member to permit the removal of the mold, and a tubular flask member slidably inclosing the sprue pin and the bowl forming member for receiving an investment compound while in a fluid state to form when hard a mold having an integral crucible portion, said body member being first

removed from the flask member to permit the removal of the crucible bowl forming member.

3. Means for forming a mold, comprising
5 a body member having a pin opening in its upper portion and grooves on one side, a sprue pin removably extending into said opening for supporting a disappearing pattern, a crucible bowl forming member slidably removably connected to the body member, there being a dovetail groove and guide 10 connection between the two members, and a tubular flask member having an offset portion slidably extending into the
15 body member grooves and inclosing the sprue pin and the crucible bowl forming member for receiving an investment compound while in a fluid state to form when hard a mold having an integral crucible
20 portion, said body member being first removed from the flask member to permit the removal of the crucible bowl forming member.

4. Means for forming a mold, comprising

a body member having a shouldered portion 25 and a pin opening in its upper portion and grooves on one side, a sprue pin removably extending into said opening for supporting a disappearing pattern, a crucible bowl forming member slidably removably connected to the body member, there being a dovetail groove and guide 30 connection between the two members, and a tubular flask member having an offset portion slidably extending into the body member 35 grooves and inclosing the sprue pin and the crucible bowl forming member for receiving an investment compound while in a fluid state to form when hard a mold having an integral crucible portion, a portion of 40 said flask member extending over the shouldered portion of the body member, said body member being first removed from the flask member to permit the removal of the crucible bowl forming member. 45

In testimony whereof, I affix my signature.

ROLLAND T. CASE.
